(57) CLAIM

The ornamental design for heel and ankle protector cup, as shown and described.

DESCRIPTION

FIG. 1 is a perspective view of a heel and ankle protector cup and showing my new design;

FIG. 2 is a side view thereof, the opposite side view being a minor image;

FIG. 3 is a front view thereof;

FIG. 4 is a rear view thereof;

FIG. 5 is a top view thereof; and,

FIG. 6 is a bottom view thereof.

The broken lines in FIG. 2 showing a foot are for illustrative purposes only and form no part of the claimed design.
